UNITED STATES PATENT OFFICE.

FRANK FABIAN, OF ALLENTOWN, PENNSYLVANIA.

MACHINE FOR BUTTERING ROLLS.

Application filed February 7, 1924. Serial No. 691,278.

To all whom it may concern:

Be it known that FRANK FABIAN, citizen of the United States, residing at Allentown, in the county of Lehigh and State of Pennsylvania, has invented certain new and useful Improvements in Machines for Buttering Rolls, of which the following is a specification.

This invention relates to machines for applying butter to rolls and it consists in the novel features hereinafter described and claimed.

An object of the invention is to provide a machine of the character stated which is of simple and durable structure and which includes means for conducting the rolls or pastry toward a buttering mechanism and at which point the butter is applied to the surfaces of the rolls or pastry whereby the same are prepared for baking and the application of the film of butter will prevent the rolls or pastry from sticking to the baking pan during the baking process.

In the accompanying drawings:

Figure 1 is a longitudinal sectional view of the machine for buttering rolls.

Figure 2 is a transverse sectional view of the same.

Figure 3 is a transverse sectional view of the butter applying mechanism.

Figure 4 is an enlarged sectional view of a tank or receptacle used in the butter applying mechanism.

Figure 5 is a top plan view of a buttering trough used in the machine.

Figure 6 is a horizontal sectional view of the tank of the butter applying mechanism cut on the line 6—6 of Figure 3.

The buttering machine or apparatus comprises a casing 1' having a shaft 1 journaled transversely therein and provided along its length and between the side walls of the casing with a roller 2. A roller 3 is journaled in the casing 1' at the same level as that at which the roller 2 is located and a belt 4 is trained around the rollers 2 and 3. Cross slats 4' are mounted upon the belt 4 and are spaced from each other at regular intervals apart. A cross strip 5 is fixed at its ends to the opposite sides of the casing 1' and is provided at the lower portion of its rear edge with a flange 6. The under forward edge of the strip 5 is concaved as at 6' and the said concavity is disposed over the upper portion of the roller 2 and at the delivery end of the belt 4. A pivot rod 7 is fixed

to the casing 1' and a table 8 is tiltably mounted upon the said rod 7. The upper surface of the table 8 normally lies in the same plane as that in which the upper surface of the strip 5 lies and the forward edge of the table 8 normally rests upon the flange 6 provided upon the strip 5. The table 8 is provided at its under side and in the vicinity of that edge which rests upon the flange 6 with a depending lug 10 and a spring 9 connects the lug 10 with the side of the casing 1' whereby the table is normally and resiliently held with its upper surface in alignment with the upper surface of the strip 5.

A shaft 11 is journaled in the upper portion of the casing 1' and a series of radially disposed arms 12 is mounted upon the shaft 11. A gear wheel 13 is fixed to the shaft 11 and is disposed beyond the exterior surface 75 of the casing 1'. A gear wheel 14 is mounted upon the shaft 1 and meshes with the gear wheel 13 whereby the shafts 1 and 11 are rotated in unison.

By means which will be hereinafter explained, the shaft 1 is rotated and the rolls, or lumps of pastry, are placed upon the upper run of the belt 4. The upper run of the said belt moves toward the strip 5. The rolls or the lumps of pastry are engaged by the arms 12 as they rotate about the axis of the shaft 11 and the said arms force the rolls over the strip 5 and upon the upper surface of the table 8. The rolls when in position upon the table 8 receive films of butter or grease whereby their surfaces are covered with films and the rolls or lumps of pastry are then in condition to be placed in baking pans and subjected to a baking process and the sticking of the rolls or pastry to the baking pan is prevented. Means are provided for ejecting or passing the buttered rolls or lumps of pastry from the table 8 and such means will be explained hereinafter.

The butter applying mechanism includes a trough 15 which is provided with a convexed bottom and which is disposed transversely across the casing 1' and disposed above the intermediate portion of the table 8. The trough 15 is provided at its sides and in the vicinity of its edges with apertures 15'. Blocks 16 are secured to the ends of the trough 15 and are slidably mounted in slots 17 provided in the side walls of the casing 1'. Rods 16' are secured at their lower ends to the blocks 16 and their upper ends are disposed through openings 17' pro-

vided in the top of the casing 1'. The said rods will prevent the blocks 16 and the trough 15 from turning or twisting during the vertical movement of the same. Pivot pins 18 are mounted at the outer sides of the blocks 16 and rods 20 are pivoted at their upper ends upon the said pins 18. The lower ends of the rods 20 are pivoted to cranks 19 which are carried by a power shaft 21 journaled in the lower portion of the casing 1'. A gear wheel 23 is mounted upon the shaft 21 and meshes with a gear wheel 22 journaled at the outer surface of the casing 1'. The gear wheel 22 meshes 15 with the gear wheel 14 hereinbefore described. Therefore as the shaft 21 rotates, rotary movement is transmitted through the intermeshing gear wheels 23 and 22 to the gear wheel 14 and at the same time the rods 20 are moved longitudinally whereby the blocks 16 and the trough 15 are moved vertically in the upper portion of the casing 1'.

A sleeve 18' is mounted upon the top wall of the trough 15 at a point between the ends 25 of the said trough and at its upper end portion slidably receives the lower end of a nipple 19'. A stop collar 25 is mounted upon the nipple 19' and a coil spring 26 is interposed between the said stop collar and 30 the upper end of the sleeve 18' and is under tension with a tendency to hold the sleeve 18' and the attached trough 15 in a lowered position. A nut 27 is mounted upon the sleeve 18' and the lower end of the spring 35 26 bears against the said nut. The said nut is adjustable upon the sleeve 18' and by adjusting the nut upon the sleeve, the tension of the spring 26 may be regulated.

Rollers 28 and 29 are journaled in the casing 1' and a belt 30 is trained around the said rollers 28 and 29. The delivery edge of the table 8 is disposed above the upper run of the belt 30. A series of cross slats 30' is mounted upon the exterior surface of the belt 30. A rod 33 is mounted for movement in guides 33' provided upon the casing 1' and the upper end of the said rod 33 is disposed below the lower surface of the lug 10 of the table 8. A cam 34 is mounted 40 upon the shaft 21 and a lug 35 is carried by the rod 33 and is disposed in the path of movement of the cam 34. A nut 36 is adjustably mounted upon the rod 33 and a coil spring 37 is interposed between the said nut 50 36 and the under surface of the upper bearing 33' which receives the rod 33. Under the compression of the spring 37 the rod 33 is normally held in a lowered position and its downward movement is limited by a 55 collar 38 which is mounted upon the said rod and is adapted to bear against the upper surface of the lower bearing 33'.

Therefore as the shaft 21 rotates the cam 34 comes in contact with the lug 35 and 60 lifts the rod 33 against the compression of

the spring 37. The upper end of the rod 33 comes in contact with the lower surface of the lug 10 and the table 8 is tilted upon the pivot rod 7. This tilting movement takes place after the butter has been applied 70 to the rolls or the lumps of pastry and the rolls or pastry slide off of the upper surface of the table 8 and fall upon the upper run of the belt 30. The shaft of the roller 28 carries a gear wheel 37' which meshes with 75 the gear wheel 22 hereinbefore described, and in that the gear wheel 22 is rotated from the shaft 21 as hereinbefore described, rotary movement is transmitted to the roller 28 whereby the belt 30 is moved in an orbit about 80 the rollers 28 and 29 and the rolls or lumps of pastry which have been deposited upon the upper run of the belt 30 are conveyed away from the delivery end of the table 8 and may 85 be received in pans or other receptacles preparatory to be subjected to the baking process and in a usual manner,

A butter or oil reservoir 39 is mounted upon the top of the casing 1' and the nipple 19', hereinbefore described, communicates 90 with the interior of the reservoir through the bottom thereof. A false bottom 40 is located in the reservoir 39 and is provided with a central opening 41 disposed in alignment with the axis of the nipple 19'. Guide rods 42 are mounted upon a partition wall 43 located in the reservoir 39. A follower plate 44 is slidably mounted upon the guide rods 42. The said follower plate 44 is also 95 slidably mounted upon a stem 45 which extends down into the nipple 19'. A stop collar 46 is carried by the stem and is adapted to close over the opening 41 of the false bottom 40 when the reservoir 39 is emptied 100 of its contents. A plate 47 is mounted upon the upper portion of the stem 45 and is housed within the reservoir 39. A coil spring 48 is interposed between the follower plate 44 and the plate 47 and serves to hold the said plates spaced from each other. A 105 coil spring 49 bears at one end against the plate 44 and at its other end bears against a stop collar 50 mounted upon the stem 45. The spring 48 serves to resiliently support the stem 45 and holds the stop 46 against the under side of the follower plate 44. A 110 nut 51 is adjustably mounted upon the upper end of the stem 45 and a spring 52 is interposed between the said nut 51 and the plate 47 and passes through an opening in the top of the reservoir 39. The spring 52 serves to hold the plate 47 spaced from the top of the reservoir 39. The reservoir 39 is provided with a nipple 53 through which the oil or butter may be poured into the 115 said reservoir.

As the pastry moves under the trough 15, during the reciprocating operation thereof through the medium of the arms 20 as before described, the same will be formed with 120

a plurality of valleys in successive spaced parallel relation by said trough, in order to divide the dough and pastry into rolls, which are buttered, as the same flows out of the 5 openings in the trough 15. Previous to this however a quantity of oil or butter has been placed in the reservoir 39 and is disposed upon the partition wall 43. The stem 45 is then inserted down through the oil or butter 10 and passed into the nipple 19' and the follower plate 44 bears against the upper surface of the oil or butter and is slidably mounted upon the pin 42.

The reservoir 39 is closed and consequently 15 the oil or butter contained within the reservoir is subjected to a pressure from the follower plate 44 and the oil or butter flows down through the opening 41 and the nipple 19' and sleeve 18' and enters the trough 15.

20 As the said trough 15 is reciprocated vertically in the operation of the machine, the said oil or butter flows out through the openings 15' and forms a film over the rolls or lumps of pastry and consequently the 25 surfaces of the rolls or lumps of pastry are buttered or greased and they will not stick to the baking pan during the process of baking and as hereinbefore indicated.

Having described the invention, what is 30 claimed is:

1. An apparatus for applying butter to rolls comprising a casing, means for feeding the rolls successively into the casing, a tilt- 35 able table located in the casing and adapted to receive the rolls, butter applying means located above the table, and means for simultaneously operating the roll forcing means, the table and the butter applying means.

2. An apparatus for applying butter to 40 rolls comprising a casing, means located in the casing for forcing the rolls successively therein, a tilttable table located in the casing and adapted to receive the rolls, butter applying means located within the 45 casing and positioned above the table, a reservoir mounted upon the casing, means for conducting the butter from the reservoir to the butter applying means, and means for simultaneously operating the roll forcing means, the table and the butter applying means.

3. An apparatus of the character de- 50 scribed comprising a casing, a shaft jour-

naled therein and provided with radially disposed arms, a table tiltably mounted in 55 the casing and adapted to receive the rolls and which are positioned thereon by the movement of the arms, butter applying means located within the casing above the table, and means for simultaneously rotat- 60 ing the shaft, tilting the table and operating the butter applying means.

4. An apparatus for applying butter to rolls comprising a casing, means for forcing the rolls successively into the casing, a 65 table tiltably mounted in the casing and adapted to receive the rolls, spring means for retaining the table in a normal roll receiving position, butter applying means located within the casing and disposed above 70 the table, and means for simultaneously actuating the roll forcing means, tilting the table and operating the butter applying means.

5. An apparatus for applying butter to 75 rolls comprising a casing, means for forcing the rolls successively into the casing, a table tiltably mounted in the casing, spring means for returning the table to normal position, butter applying means located 80 within the casing and disposed above the table, a shaft journaled in the casing, means operatively connecting the shaft with the roll forcing means, a spring pressed rod mounted adjacent the shaft and having a 85 lug, a cam carried by the shaft and adapted to engage the lug to move the rod, the upper portion of the rod being disposed under the free end of the table and means operatively connecting the shaft with the butter apply- 90 ing means.

6. An apparatus for applying butter to rolls comprising a casing, means for forcing the rolls successively into the casing, a 95 table pivotally mounted in the casing and adapted to receive the rolls, means for tilting the table, butter applying means comprising a trough movably mounted in the casing, a reservoir mounted on the casing, a nipple connecting the reservoir with the 100 trough whereby the trough may have movement relative to the reservoir, and a spring pressed follower located in the reservoir.

In testimony whereof I affix my signature.

FRANK FABIAN.
